UNITED STATES PATENT OFFICE.

DOSSABHOI SHAPOYE FRASER, OF BOMBAY, INDIA.

SADDLE-SUPPORTING DEVICE FOR CYCLES.

SPECIFICATION forming part of Letters Patent No. 658,909, dated October 2, 1900.

Application filed December 2, 1899. Serial No. 738,955. (No model.)

To all whom it may concern:

Be it known that I, DOSSABHOI SHAPOYE FRASER, a subject of Queen Victoria, Empress of India, and a resident of Bombay, India, have invented new and useful Improvements 5 in Saddle-Supporting Devices for Cycles and the Like, (for which I have filed an application for British Letters Patent No. 21,391, dated October 26, 1899,) of which the following is a 10 specification.

This invention relates to an improved device for supporting in a yielding manner the seat-pillars of cycles and like vehicles; and it consists of a self-contained device applicable 15 to existing cycles in which the seat-pillar is supported in an unyielding manner by being nipped by a bolt in the seat-bracket at the top of the diagonal frame-tube without any alteration of the cycle itself, whereby 20 such disadvantages as appertain to such existing devices of the kind which require the cycle to be altered or adapted to them are avoided, the improved device thus permitting of the advantages of a yielding seat-pillar 25 being more generally obtained.

On the accompanying drawings, Figure 1 represents the improved device in sectional elevation, showing the same applied to an ordinary cycle-frame shown in dotted outline. 30 Fig. 2 represents a sectional plan on 2 2, Fig. 1, without representing the cycle-frame. Fig. 3 represents a like view on 3 3, Fig. 1; and Fig. 4 represents a like view on 4 4, Fig. 1.

In carrying out the invention I arrange 35 within the upper end of an incasing tube 1 a guide-tube 2, locating the same in the tube 1 in a separable manner by screws 3, and I arrange within the tube 2 the stem or downward member 4 of the seat-pillar, locating the 40 same in the tube in a separable manner and also in such a manner as to allow of limited endwise or falling and rising movements of the seat-pillar and as to prevent rotative movements thereof by screws 5, working in 45 slots 6, made in the tube 2. I also arrange within the lower end of the tube 1 an internally-screw-threaded collar 7, locating the same in the tube in a separable manner by screws 8, and within and engaging with such 50 collar I arrange in an adjustable manner an externally-screw-threaded elongated tubular bolt 9, having a flange 10 at its top end and being nicked at 11 at both its top and bottom ends to facilitate its placement and its ad-

justment in the collar 7 by means of a screw- 55 driver or the like.

Between the bottom of the seat-pillar stem and the top of the adjustable bolt 9 I arrange a helical spring 12, preferably locating the spring ends in flanged caps 13, which respectively bear against the adjacent pillar-stem and bolt ends and act as seatings to the spring ends. The adjustable bolt 9 enables the resistance of the spring 12 to be readily accommodated to the weight of the rider upon the 60 bolt being screwed up or down in the collar 7 from its bottom nick 11, as may be required. The seat-pillar stem can at any time be withdrawn from the tube 2 without releasing the spring 12 by removing the screws 5 through 70 holes 14 in the tube 1.

The device thus forms a self-contained cycle auxiliary as an entity applicable to and removable from the diagonal frame-tube 15 of a cycle without any alteration of the latter and is located within the ordinary seat-bracket 16 by the ordinary nut and bolt 17 exactly in the manner in which the ordinary seat-pillar is located in a rigid or unyielding manner, but with the advantage of obtaining 80 a yielding seat-pillar. The device also allows of any desired adjustment of the height of the seat to suit different riders without requiring any alteration in the adjustment or relation of its parts and simply by slackening and refastening the nut 17 and raising or lowering the device as required.

What I claim as my invention, and desire to secure by Letters Patent, is—

A device for supporting in a yielding manner the seat-pillars of cycles and the like, consisting of the combination with an incasing tube, of a guide-tube therein having longitudinal slots, a seat-pillar fitting in said guide-tube and carrying studs engaging with said 90 slots, a nut secured in the incasing tube below the ends of the guide-tube and seat-pillar, a screw meshing with said nut, flanged caps on said screw and under the ends of the 95 guide-tube and pillar, and a helical spring 100 between said caps.

In testimony whereof I have signed this specification in the presence of two subscribing witnesses.

DOSSABHOI SHAPOYE FRASER.
